Wm. Lancaster & Allwine

UNITED STATES PATENT OFFICE.

JOSEPH BACHRIK, OF SMITHDALE, PENNSYLVANIA.

RAILWAY TIE-PLATE AND ANTICREEPER.

Application filed May 18, 1922. Serial No. 561,982.

To all whom it may concern:

Be it known that I, JOSEPH BACHRIK, a citizen of the United States, residing at Smithdale, in the county of Allegheny and State of Pennsylvania, have invented certain new and useful Improvements in Railway Tie-Plates and Anticreepers, of which the following is a specification.

This invention relates to railways and the primary object of the invention is to provide a novel means for connecting the railway ties and rails together, so as to facilitate and expedite the removing and placing of rails from and on the ties and so that the rails will be firmly connected with the ties to prevent the pulling of the rails from the ties under all conditions and to effectively prevent the creeping of the rails in relation to the ties.

Another object of the invention is the provision of a tie plate for receiving the rails, the plate having novel locking means for engaging the rails which will effectively prevent the creeping of said rails, said locking means including sliding wedges which tend to move in tighter locking engagement with the rails during vibration of the rails.

A further object of the invention is to provide novel means for locking the locking wedges for the railway tie against movement in one direction, so that the said locking wedges will be prevented from moving out of engagement with the rails under all conditions.

A further object of the invention is the provision of a railway tie plate which can be rigidly secured to a cross tie, and which embodies a sliding locking wedge for firmly locking the rail to the tie plate, the wedge constituting the only means necessary to remove from the plate when it is desired to remove the rail from the plate or to place a rail on the plate and tie.

A still further object of the invention is to provide an improved anti-rail creeping plate of the above character, which is durable and efficient in use, one that is simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying

drawings, forming a part of this specification, in which drawings:

Figure 1 is a perspective view of a railroad rail and tie, showing the improved rail plate and anti-creeper connected therewith.

Figure 2 is a plan view of the improved railroad plate and anti-creeper.

Figure 3 is an end elevation of the combined railroad plate and anti-creeper showing a rail connected thereto, the rail being shown in transverse section.

Figure 4 is an enlarged fragmentary detail perspective view of a portion of the improved railroad tie plate, and

Figure 5 is an enlarged detail perspective of the novel locking wedge provided for firmly locking the rail on the tie plate.

Referring to the drawings in detail, wherein similar reference characters designate corresponding parts throughout the several views, the letter A generally indicates the combined railway tie plate and anti-creeper; B, a railroad tie; and C, a rail.

The rail C and the tie B have been merely shown to illustrate the use of the improved combined railroad tie plate and anti-creeper and are of the usual construction. The tie B consists of the rectangular shaped body 10.

The rail C comprises the ball or tread 11 and the base flanges 12 and 13.

The improved combined railroad tie plate and anti-creeper A includes a rectangular shaped base plate 15 which can be made of a width sufficient to cover or extend across the entire top face of the tie B. This plate 15 can have its lower surface formed smooth if so desired, so as to form a flat face for engaging each tie. The body 15 is provided at a point equidistant its ends with a transverse rail seat 16 and the body at one edge of the seat is provided with an upstanding transversely extending rib 17 for engaging one flange of the rail C. As shown, this rib 17 is adapted to engage the outer edge of the flange 12 of the rail. One end of the rib 17 is provided with an inwardly extending flange 18 which is adapted to overlie the base flange 12 and serves as means for effectively preventing rising movement of the rail in relation to the plate. The body 15 diagonally opposite the flange 18 at one side of the rail seat 16 is provided with an enlargement 19 and this body and enlargement 19 is provided with an inwardly extending wedge 110

shaped groove 20. This groove 20 extends transversely of the plate or body 15 and terminates substantially at the longitudinal center thereof. The side walls of the groove 20 are undercut as at 21 to provide guide ways, the purpose of which will be herein-after more fully described.

The body 15 has slidably associated therewith the novel locking means D which 10 firmly connects the rail with the tie. This locking means D consists of the wedge shaped body 25 having outwardly extending base flanges 26 formed on its longitudinal edges which are adapted to engage in 15 the undercut portions 21 formed in the walls of the groove 20. This body 25 slidably fits within the wedge shaped groove 20 and it can be seen that when the same is driven into the groove, the body 25 will be forced 20 into intimate engagement with the base flange 13 of the rail. The body 25 protrudes above the groove 20 so as to permit the inner edge of the same to engage the outer edge of the base flange 13 of the rail. 25 An inwardly extending overhanging flange 28 is formed on one end of the body 25 and this flange is adapted to overlie and to intimately engage the upper surface of the base flange 13 of the rail C as clearly shown in 30 Figure 1 of the drawings. In order to form an effective guide for the body 25, the flange 28 is provided with an oppositely extending guide flange 29 which is adapted to overlie and slidably engage the upper surface of the 35 enlargement 19 as clearly shown in Figure 2 of the drawings. This guard flange 29 has its outer end notched or curved inwardly as at 30 for forming a seat as will be herein-after more fully apparent as the description 40 proceeds.

If so desired, the body 15 of the plate on opposite sides of the rail seat 16 can be provided with openings 31 for receiving spikes 32 and these spikes 32 will serve as means 45 for holding the plate in intimate contact with the tie. The heads of the spikes 32 are adapted to overlie the base flanges 12 and 13 of the rail as can be clearly seen in Figures 1 and 3 of the drawings.

50 If so desired, the body 15 of the plate can also be provided at diagonally opposite points with openings 33 for the reception of screw spikes 34. These screw spikes form an efficient means for connecting the plate 55 with the tie to effectively prevent disengagement of the plate therefrom. One opening 33 is formed in the enlargement 19 and the bolt which is adapted to extend in this opening has mounted thereon an eccentric locking washer 35 which is adapted to engage in the seat 30 for preventing the accidental withdrawal of the lock D from the groove 20.

In use of the improved combined tie plate 60 and anti-creeper, the same is laid upon the

tie B and secured thereto by one of the spikes 34, after which the rail C is placed upon the rail seat 16. The lock D is then forcibly driven into the wedge shaped groove 20 which will firmly lock the rail to 70 the tie plate. The other screw spike 34 with the eccentric washer 35 is placed in position. The washer 35 is knocked into tight engagement with the seat 30 so as to prevent outward movement of the lock D, and the spike 75 34 is then tightened so as to firmly hold the eccentric washer against movement. The spikes 32 can now be driven in place if so desired.

Now, when it is desired to remove the rail 80 through any reason from the tie B, it is merely necessary to loosen the screw bolt 34, which is adjacent to the lock D so as to permit the lifting of the eccentric washer 35 above the guide flange 29, after which the 85 rail lock D can be driven outwardly from the groove 20. This will permit the lifting of the rail C from off of its seat 16.

It is preferred to make the plates right and left hand so that the locks D can extend 90 in the direction of travel on double rail lines. Thus, it can be seen any tendency of the rails to creep will tend to drive or force the locks D further into the grooves 20 and thus bring the locks D into tighter engagement with the rails. This, of course, will 95 effectively prevent the creeping of the rails.

This improved plate will also effectively prevent the spreading of the rails in that movement of the rails on the plates is 100 absolutely prevented. Also turning over of the rails will also be effectively prevented.

The improved tie plate and anti-creeper will be found especially valuable where 105 tracks are laid in swampy ground in that disengagement of the rails from the ties through rising and lowering movement of the ties in the swampy ground will be prevented.

Changes in details may be made without 110 departing from the spirit or scope of this invention; but,

I claim:

1. In a tie plate and anti-creeper, a base plate provided with a transversely extending rail seat formed on the upper surface thereof, a transversely extending rail flange engaging rib formed on the plate at one side of the rail seat, the plate having an inwardly extending wedge shaped groove 120 formed therein on the other side of the seat, a rail lock including a wedge shaped body adapted to be driven into the wedge shaped groove arranged to extend into the upper surface of the plate for engaging the side 125 flange of a rail, an overhanging flange formed on the body of the lock for overlying the base flange of the rail, and rotatable locking means carried by the plate for engaging the body of the wedge shaped block 130

to prevent accidental movement thereof from out of the wedge shaped groove.

2. In a guide plate and anti-creeper, a base plate having a rail seat formed on its upper face; an overhanging flange formed on the plate at one side of the seat for engaging one base flange of a rail, the plate having an inwardly extending wedge shaped groove formed therein on the other side of the rail seat and diagonally opposite the rail base engaging flange, a lock including a wedge shaped body adapted to be driven into the groove, an overhanging rail base engaging flange carried by the wedge shaped body of the lock, a guide flange formed on the body of the lock arranged to engage the upper surface of the plate, a screw bolt associated with the plate, and a cam washer rotatably mounted upon the screw bolt for locking engagement with the lock to prevent accidental movement thereof from out of the groove.
3. In a tie plate and anti-rail creeper, a base plate provided with a rail seat at its upper surface, a transversely extending rail flange engaging rib formed on the base plate at one side of the rail seat, an overhanging rail engaging flange formed on one end of the rib, the base plate having an inwardly extending groove formed therein of wedge shape on the opposite side of the rail seat from said rib, an enlargement formed on the base plate, a rail lock slidably mounted within the wedge shaped groove, an overhanging flange carried by the lock for engaging one of the base flanges of a rail, the walls of the groove being under cut to provide guide ways, base flanges formed on the lock for engaging in said guide ways, a guide flange formed on the lock for slidably engaging the upper surface of the enlargement, said flange having an arcuate seat formed on one end thereof, a screw bolt associated with the enlargement, and an eccentric washer rotatably mounted upon the screw bolt for fitting in the seat of the guard flange for holding the lock against movement in one direction.

JOSEPH BACHRIK.
